Claims priority, application Great Britain Mar. 22, 1961
3 Claims. (Cl. 114—126)

This invention relates to stabilising apparatus for ships. It is already known to provide apparatus incorporating a stabilising fin pivotally mounted about a pivot pin so that it can be swung out of a cavity provided therefor and returned into this cavity and which is also pivotally mounted about an axis which is at right angles to the axis through the said pivot pin. It is also known to provide a rotary vane drive motor having an outer casing to which the fin is fixed and an inner casing surrounding and fixed to a shaft which is held in a support against rotation about its axis and which supports the fin, the outer casing being furnished with vanes projecting radially into the annular space between the casings, and the inner casing presenting axial partitions projecting radially outwards into the annular space between the casings, a vane being arranged between every pair of adjacent partitions.

A rotary vane motor as described is normally constructed with small clearances and any appreciable relative movement between the inner and the outer casing would impair seriously the efficient operation of the motor.

It is an object of the present development to provide a construction in which lateral movement or deflection of the fin relative to the shaft or deflection of the shaft itself will not impair the efficiency of the rotary vane drive motor.

A stabilising apparatus for a ship according to the present development incorporates a rotary vane drive motor for the fin in which the outer casing is coupled to the fin by a resilient coupling which constrains the fin to rotate with the casing but otherwise permits relative movement between the fin and the casing, and the inner casing is coupled to the shaft but spaced therefrom over at least the greater part of its length.

The fin may present axially projecting pins penetrating a portion of the outer casing, resilient bushes being interposed between the pins and the outer casing. The portion of the outer casing penetrated by the pins may be constituted by a radially projecting flange or radially projecting lugs.

The inner casing is preferably attached to the shaft at the end of the casing adjacent to the pivot pin.

A practical embodiment of the invention is illustrated in the accompanying drawing in which FIG. 1 is a vertical section of a stabilizing apparatus, FIG. 2 is a view to a larger scale of the resilient coupling in FIG. 1, and FIG. 3 is a section through the line 3—3 in FIG. 1. In the drawings 1 denotes a non-rotary fin shaft held at one end in a support constituted by a socket 2 presenting pins 2A engaging fixed bearings 3 so that the fin shaft 1 is able to swing in a plane normal to the axis of the pins 2A. 4 denotes a fin mounted on bearings 5 and 6 on the shaft 1 so that the fin is rotatable about the shaft 1. 7 denotes the outer casing of a vane drive motor having inwardly projecting vanes 7A, said outer casing presenting lugs 8 carrying resilient bushes 9 penetrated by pins 10 fixed to the fin 4, and 11 denotes the inner casing of the

2

vane drive motor through the centre of which the shaft 1 passes, said inner casing being furnished with partitions 11A projecting radially upwards between the vanes 7A into the annular space 7B between the casings 7 and 11. The casing 11 is spaced from the fin shaft 1 for the greater part of its length, being in contact with the fin shaft 1 only at the position 12 for the purpose of facilitating centering of the vane drive motor on the fin shaft 1, and is coupled to the fin shaft 1 by way of a coupling 13 consisting of two flanges 13A connected by bolts 13B and the socket 2. 14 denotes a dust and grit-excluding casing fixed to the fin 4 and engaging the socket 2 by way of a gland 15. 16 denotes a sleeve of low-friction material interposed between the casings 7 and 11 and 17 denotes packing to prevent escape of operating fluid from the space between the casings 7 and 11. 18 and 19 denote annular grooves in the inner casing 11, said grooves 18 and 19 communicating with the annular space 7B on opposite sides of the partitions 11A and being connected to respective passages 20 and 21 through which operating fluid is to be fed to, or conducted from, the grooves 18 and 19 whereby to cause the vanes 7A and thus the outer casing 7 of the connected fin 4 to perform a partial rotation in the desired direction.

In practice, the fin is moved into an operative position by swinging the shaft 1 about the pivot pins 2A to cause the fin to move outwardly from the cavity provided therefor. The fin is swung about the shaft by admitting fluid under pressure to the appropriate spaces between the vanes 7A, and the partitions 11A in the rotary vane motor 7, 11, the pressure in these compartments acting between the partitions 11A on the inner casing 11 which is held stationary by its connection with the shaft 1 by way of the coupling 13, and the vanes 7A on the outer casing 7 coupled to the fin 4 being effective to cause the outer casing 7 to rotate relatively to the inner casing 11 and to carry the fin 4 along with it. The fin 4 must consequently always follow the outer casing 7 and perform identical rotational movements. During operation of the fin lateral movement or deflection of the fin 4 relative to the shaft 1 is absorbed by the resilient coupling provided between the fin and the outer casing and constituted by the pins 10 and the resilient bushes 9, and deflection of the shaft 1 has a negligible effect on the inner casing 11 since the inner casing 11 is spaced from the shaft 1 over the greater part of its length and is in contact with the shaft 1 only at the point 12 close to the point where the shaft 1 is held in its socket. At the point 12 any normal deflection of the shaft 1 is less than the normal working clearances in the vane drive motor 7, 11. The operation of the rotary vane motor is thus not impaired by any lateral movement or deflection of the fin 4 or the shaft 1. The inner casing 11 is in contact with the shaft 1 at the point 12 to facilitate aligning of the axes of the vane drive motor and of the shaft 1.

What is claimed is:

1. A stabilizing apparatus for a ship incorporating a support, a non-rotary shaft engaged at one end with the support, a fin rotatable about the shaft, and a rotary vane drive motor having an inner casing surrounding the shaft and coupled to the shaft but radially spaced from the shaft over at least the greater part of its length, an outer casing, a flexible coupling connecting the outer casing to the fin in suchwise as to constrain the fin to rotate with the casing but otherwise to permit relative lateral movement between the fin and the casing, vanes presented by the outer casing projecting radially into the annular space between the casings, and radial partitions projecting from the inner casing into the annular space between the casings, each vane being between two adjacent partitions, and means for conducting operating fluid to and from the annular space between the casings.

2. Apparatus as claimed in claim 1 in which the resilient coupling includes axially projecting pins penetrating a portion of the outer casing, resilient bushies being interposed between the pins and the portion of the outer casing.

3. Apparatus as claimed in claim 1 in which the inner casing of the vane drive motor is in contact with the shaft only at the end of the casing adjacent to the shaft support.
